FACE BIT

William J. Mitchell, San Francisco, Calif., assignor to Chicago Pneumatic Tool Company, New York, N. Y., a corporation of New Jersey

Application May 15, 1933, Serial No. 671,265

3 Claims. (Cl. 255—61)

My present invention relates to a novel face bit of the rotary, diamond type especially for the use with machines engaged in boring or drilling grout holes for dam sites, boring blasting holes, mining, exploration work, and other similar earth boring or drilling operations. The face bit is adapted for use at the lower end of the tubular drill rod of the drilling machine, and this drill bit is readily interchangeable with a core-bit that 5 may be substituted for the face bit when an inspection-sample of the earth is desired during the boring of a hole.

The face-bit is supplied with water to assist in the cutting operations, and means are provided for passing the water from the interior of the tool to the exterior or working face of the bit where it is uniformly distributed in the cutting or boring area without materially reducing the area of the diamond cutters, and means are provided for conveying the débris or cuttings of the 10 tool to the annular space between the rotary tool and the wall of the bored hole in order that the débris may be lifted by the water to the surface of the drilled ground.

By the utilization of the bit of my invention I have in actual practice enhanced the speed of boring operations, materially reduced the expense and time of operating a drilling machine, increased the durability of the usual bits, and provided a reliable and strong drilling bit that may be rotated at greater speed than the speed of the ordinary bits now in use.

My invention consists in certain novel combinations and arrangements of parts as will hereinafter be more fully set forth and claimed. In the accompanying drawing I have illustrated several examples of the novel features of my invention wherein the parts are combined and arranged according to modes so far devised for the practical application of the principles of my invention. While the illustrated tool is successfully operating in actual practice, it will be understood that the exemplified structures may be altered or changed, within the scope of my claims, without departing from the principles of my invention.

Figure 1 is a side view at the lower or bit end of a rotary tubular drilling tool equipped with the face bit of my invention. Figure 2 is an enlarged view similar to Figure 1, but showing the face bit equipped with a special tapered reaming device, and also showing the face bit partly broken away for convenience of illustration.

Figure 3 is a face view of the bit, showing the

staggered arrangement of the water-distributing holes, and showing, for convenience of illustration only a sector or segment of the cutting face set with diamond cutters, and Figure 4 is a similar view showing the radially extending, curved conveyor grooves for the débris. Figure 5 is a side view of the bit of Figure 4. Figure 6 shows one of the bits equipped with a cylindrical coupling having reaming cutters.

The face bit of my invention is attached at the 10 lower end of the lowest tubular section of the usual tubular drill rod, as 1, and the bit 2 is fastened with an exteriorly threaded shank 3 which is threaded into the complementary interior threads of the tubular section of the drill rod. 15 As shown, the bit is hollow and has an exterior diameter slightly less than the bore of the drill rod in order that the water may flow downwardly through the tubular rod to the rounded interior chamber of the bit.

The cutting face 4 of the bit is tapered, rounded, circular or preferably, as shown, hemispherical, and merges with the exterior cylindrical periphery of the bit proper. The cutting face is provided with the usual diamond cutters 5 that 25 are set in proper manner in the metal of the face, for the cutting or drilling operation, and in addition to these cutters 5, an annular series of reaming cutters 6 is set in the cylindrical portion of the bit for the purpose of enlarging the hole 30 as it is bored. The enlarged hole, as will be understood, provides an annular space around the exterior of the drill rod for the upward flow of water and débris from the cutting face of the bit.

Water flowing down through the interior of 35 the drill rod reaches the interior of the hollow bit, and is passed to the exterior of the face through holes as 7, 8, and 9, which, as indicated in Figures 3 and 4 are staggered, that is, spaced at unequal distances from the center of the bit, 40 in order that the metal face may not be materially weakened, and in order that the cutters 5 may be set to the face of the bit to accomplish a maximum result in the cutter operation. The holes are so staggered that one of these non-cutting 45 portions of the face will not follow another non-cutting portion as the bit rotates, and this staggered arrangement of the holes distributes the water over an area of the face from near the center of the bit to approximately that portion of 50 the cutting face having the maximum diameter. By the means, the water passing through the holes 7, 8, and 9, is uniformly distributed over the entire cutting face of the bit to facilitate the cutting operation, as the bit rotates or revolves.

- These holes 7, 8, and 9, in the wall of the bit, are enlarged as at 9' where they open into the interior chamber of the head of the bit in order to prevent clogging of the holes by the débris. 5
- Thus, should the débris be forced into the holes against the down flow of the water in the tool, the enlarged inner portions of the holes permits the débris to spread and the flow of water insures a loose condition in the débris that eliminates 10 clogging or packing of the holes.

In order to convey the cuttings or débris away from the cutting face of the bit, and thus prevent clogging and inefficient work of the bit, I provide a series of grooves 10, here shown as three in 15 number, but it will be understood that the number of grooves may be varied. These grooves 10 are fashioned in the cutting face and extend from the center of the face of the bit to the annular periphery of the bit, starting at the center with 20 a zero depth and increasing in depth and width to their outer ends where the maximum depth and width is attained. Preferably the grooves extend radially from the center, with a curved formation, so that the trailing edges of the 25 groove, as the bit rotates, tends to pass or convey the débris from the center toward the periphery of the bit face. The water flowing through the holes 7, 8, and 9, assists in conveying the débris or cuttings to the periphery of the bit 30 face, and then the upwardly moving column of water in the annular space about the exterior of the drill rod lifts this débris to the ground surface.

In Figure 2 I have shown the face bit in use 35 with a coupling section 11 that is attached at the lower end of the drill rod section 1, and the hollow face bit is threaded in the lower end of this coupling. At its lower end the coupling is fashioned with an annular, tapered or beveled face 40 12 having its smaller diameter complementary to the outer diameter of the bit, and its larger diameter complementary to the larger exterior periphery of the drill tool section 1. In this conical, tapered or beveled face 12 are set the diamond 45 cutters 13, which, in addition to the annular series of reamers 6 of the bit, serve as reaming cutters for enlarging the bored hole. These reaming cutters as shown are set up above, or spaced above, the cutters on the bit, and they are especially advantageous in some boring or drilling operations where reaming of the bored hole is required. 50

In Figure 6 a cylindrical coupling 14 is illustrated, which may be employed in lieu of the tapered coupling 11 in Figure 2, and this coupling is provided with the reaming cutters 13 some distance above the face of the bit to enlarge the hole. 55

As thus constructed and arranged the drill 60 is capable of boring a straight hole through the earth regardless of the nature of the soil, with a speed not heretofore attainable with drill bits now in use. The presence of the water which flows down through the drill tube and carries the débris up through the hole, eliminates the creation of dust that usually accompanies drilling and boring operations of this nature, and as this 65

dust is unhealthy and unsanitary, it will be apparent that the attendants or operators working about the hole are protected from the deleterious effects of dust. The smooth and easy operation of the drilling tool permits the use of a compactly arranged electric motor for supplying the power to the machine, a use not attainable under ordinary conditions where a "hammer" type of drill is used. 5

During the boring operations, if it is desired to 10 employ a core bit, to extract the sample of the earth through which the bit is passing, the drill rod may be withdrawn, the face bit removed, and a core bit substituted therefor, with convenience and without material loss of time. After a sample 15 has been secured the tool may again be withdrawn, and the face bit substituted for the core bit.

In actual practice the face bit of my invention 20 has proven highly satisfactory in materially reducing the cost of maintenance of the drilling machine; in enhancing the speed at which the rotary tool may be operated, and in reducing the time required for drilling a hole, regardless of 25 the depth of the hole. 25

Having thus fully described my invention, what I claim as new and desire to secure by Letters Patent is:

1. A hollow, cylindrical, rotary, boring bit having a hemi-spherical cutting face and cutters set 30 in said face, said bit having three water holes arranged on a spiral line about the center of the bit, said water holes having a maximum cross area at the inner side of the face of the bit and a minimum cross area at the outer side of the 35 face of the bit, said bit having a groove in its face between each pair of adjoining water holes, and said grooves increasing in cross area from the center of the bit to the cylindrical periphery of the bit. 40

2. A hollow, cylindrical, rotary, boring bit having a hemi-spherical cutting face and cutters set in said face, and an annular series of reaming cutters extending laterally from the cylindrical periphery of the bit, said bit having three spirally arranged water holes in its face each having a maximum cross area at the inner side of the face of the bit and a minimum cross area at the outer side of the face of the bit, said bit also having a groove in its face between each pair of 45 adjoining water holes, and said grooves increasing in cross area from the center of the bit and terminating approximately at the line of the reaming cutters. 50

3. A hollow, cylindrical, rotary, boring bit having a hemi-spherical cutting face and cutters set in said face, said bit having a plurality of water holes arranged on a spiral line about the center of the bit, said water holes having a maximum cross area at the inner side of the face of the 55 bit, and a minimum cross area at the outer side of the face of the bit, said bit having a groove in its face between each pair of adjoining water holes, and said grooves increasing in cross area from the center of the bit to the cylindrical 60 periphery of the bit. 65

WILLIAM J. MITCHELL.
